UNITED STATES PATENT OFFICE.

WILFRED DUPRÉ, OF WORCESTER, MASSACHUSETTS.

REVERSIBLE BROOM.

Application filed January 28, 1925. Serial No. 5,330.

This invention relates to a broom having a detachable reversible filler and the principal objects thereof are to provide an improvement in the reversible filler by which 5 two advantages are secured. In the first place, short strands of broom corn can be used and in the second place, the thinner ends of these strands are at the end of the broom, where they are used, thus avoiding 10 the presence of thick and unyielding ends.

The invention also involves an improved holder for the fillers which will not injure them and will secure them firmly and which can be located in two places at different 15 distances from the handle to provide for holding within it a set of bristles that is materially worn off at the end; also a surrounding holding means for the bristles and improved means of securing the bristles together and holding them together.

Other objects and advantages of the invention will appear hereinafter.

Reference is to be had to the accompanying drawings, in which—

25 Fig. 1 is a side view of a preferred embodiment of the invention;

Fig. 2 is an edge view showing the casing open;

30 Fig. 3 is a sectional view on the line 3—3 of Fig. 1;

Fig. 4 is a sectional view on the line 4—4 of Fig. 1 on enlarged scale;

Fig. 5 is a fragmentary side view somewhat enlarged and modified;

35 Fig. 6 is an edge view of two sets of short bristles which are to be connected as indicated in Fig. 7; and

Fig. 8 is a longitudinal sectional view of the same showing an improved fastening 40 means for holding the bristles.

As stated, this invention relates to that type of broom in which the filler is removable from a holder and is also reversible end for end. In Fig. 6 I have shown two bunches 45 of broom corn each much shorter than can be used now in practice in the manufacture of brooms and therefore constituting a waste product which can be bought at a very low figure. The butt ends of these two bunches 50 10 are separated a little and brought together. The ends of the bristles which pass by each other in Fig. 7 are held in place with respect to each other by impregnating them with tar. The tar is put on in a liquid state 55 and is intended to penetrate all through them. It tends to remain sticky for a long

time. Each bundle is then bound around with twine 11.

A series of bundles may be gathered together, as shown in the other figures, especially Fig. 4, and a cloth or tape is placed around the series or a simple metal band 9 as shown in Fig. 5 or in the preferred form, a double metal strip 12. This strip extends all the way around the series or bundles to 65 form a single broom head. Also, to prevent the bristles moving endwise, I place transverse pins, nails, or other fastening devices 13 across the several bundles and then through the whole set of bundles I place another pin or rod 14 transversely to them. These pins are all headed on one side and the points headed over on the other. They all extend twice through the metal strip 12. This metal strip is provided with an integral side flange 15 on one edge and on the other edge there is a longer flange 16 which, after application to the bristles, is bent over all around, as shown especially in Fig. 8, for the purpose of covering the nail heads and 70 furnishing a strong and complete binder for the whole set of bristles. This completes 75 the formation of the removable and reversible brush head or filler. It will be seen that it has two ends substantially alike so that 80 when reversed there will be no difference in the character of the brush.

The metallic flange 16 is pierced with 85 perforations 17, preferably four in number, on each side for receiving two series of wires 18 and 19. One set of wires 19 is pivotally attached and the other 18 rigidly. These wires are used for anchoring this binding strip and consequently the brush head to a casing 20. They are located both on front 90 and back of said casing and the casing is provided with perforations 21 for receiving both sets of wires when the brush is used in the condition shown in Figs. 1 and 2, and with another set of perforations 22 farther 95 back for receiving the same wires when the brush is worn at one end and has to be shoved back farther in the casing 20.

The casing is provided with a hinged 100 cover plate 23 and of course it is this cover that receives the perforations on one side. The casing is formed of sheet metal tapering both ways to receive the brush head and allow the bristles to flare, as indicated. On the two edges near the open ends the metal 105 casing is bent out to form recesses 24 for receiving a pair of fastening devices 25, in 110

the form of wires having a straight back and two parallel legs. These can be turned in notches 24 to the position shown in Fig. 1, for holding the cover in position or to a position in which they project away from the cover so as not to engage it and allow it to be released, as shown in Fig. 2.

The casing 20 is fastened at the upper end around a wooden block 27 which extends 10 across it within and which has a pair of grooves 28 for receiving the inturned ends of the casing on opposite sides and holding it in position. It is also held in position by a pair of rivets 29 extending across it. This 15 block 27 is provided with grooves down its ends in which rest the ends 30 of a coil spring 31 or a pair of them. These ends are bent in toward each other at the bottom of this block and the spring is a straight coil spring 20 located in a concave depression in the top of the block and extending entirely across the top of it. I prefer to form this spring from a single piece of wire. This wire is bent at the center to form a loop 32 which, of course, being formed of two pieces of wire, 25 is twice as wide one way as the other. These two wires are twisted together at 33 for a purpose to be described and then are separated to form two springs 31 which I have 30 referred to as a single spring because they are continuous and act together.

The end formed of the parts 32 and 33 is driven into a hole in the end of the wooden handle 34. On account of the flat shape of 35 the loop 32, this will not turn in the handle after it has been inserted. A metal collar 35 is screwed on the twisted wire, being perforated with a hole to receive it. On account of this particular construction it cannot 40 work loose endwise. It is secured to the end of the wooden handle by a nail 36 or the like and on account of that the ferrule cannot be turned. Therefore the handle cannot work 45 loose either by turning or by longitudinal motion. This constitutes a very secure and firm way of holding it.

In operation, the handle being connected with the head or casing 20 by the spring 31, a yielding action is secured and this is particularly valuable in case of the use of short bristles of less than the ordinary length because it gives the feel of the bristled broom and the effectiveness. The casing 20 consti-

tutes a holder for the bristles which, by means of the cover 23 and the devices 25, securely holds them in place and yet they are easily and readily detachable. The wires 18 and 19 hold the metallic binding strip 12 and therefore the brush head accurately in position and allow some flexibility between the casing and the center of the brush head. This is also detachable to receive the brush when the bristles are shortened by wear after reversal. The use of the short bristles which are a waste product, is a great advantage 55 for several reasons as has been stated. The brush head is made in a very simple and convenient way and yet the parts are permanently connected by several securing devices that have been shown and described. It constitutes a material improvement over the reversible and removable brooms that have been on the market heretofore.

Although I have illustrated and described only a few forms of the invention I am aware 75 of the fact that other modifications can be made therein by any person skilled in the art without departing from the scope of the invention as expressed in the claims.

Therefore, I do not wish to be limited to all the details of construction herein shown and described but what I do claim is:—

1. In a broom, the combination of a casing for holding the broom head, said casing having converging sides and ends and having a cover constituting one side hinged to the rest of the casing, and a pair of wires pivotally mounted in the opposite edges of the casing and each adapted to be turned on itself as an axis and each having two parallel ends adapted to engage the outer surface of the cover and the opposite surface of the casing to hold the cover closed.

2. In a broom, the combination with a metallic casing, of a reversible broom head, either end of which is adapted to be inserted in said casing, said casing having perforations on its sides, a series of wires connected with said perforations, and a metallic band surrounding the reversible broom head near its center and pivotally connected with said wires to hold the broom head in definite position with respect to the casing.

In testimony whereof I have hereunto affixed my signature.

WILFRED DUPRÉ.
